WINDOW SHADE ROLLER AND CURTAIN
ROD BRACKET

Stanley Woltanski, Chicago, Ill.

Application September 22, 1941, Serial No. 411,807

1 Claim. (Cl. 248—259)

The present invention relates to brackets for the purpose of supporting thereby a window shade roller and curtain or drapery rod and has for its main object the provision of a bracket consisting of comparatively few parts which may be readily formed out of metallic sheet plate by suitably bending the same and interassembling.

A still further object of the present invention is the provision of a shade roller and curtain rod bracket of the character indicated, which may be provided with window frame engaging means, and which may be regulated depending upon the width of the window frame, preventing the use of screws or nails but relying entirely upon clamping action of the bracket.

A still further object of the present invention is to generally improve the construction of the shade roller and curtain rod bracket of the character indicated.

With the above general objects in view and others that will appear as the invention is better understood, the same consists in the novel construction, combination and arrangement of parts hereinafter more fully described, illustrated in the accompanying drawing and pointed out in the appended claim.

In the drawing forming a part of this application and in which like designating characters refer to corresponding parts throughout the several views,

Fig. 1 is a cross-sectional view on horizontal plane through the window frame, with a pair of brackets in operative association therewith, and illustrating the manner in which a shade roller, a curtain rod and a drapery rod may be supported by a pair of brackets constituting the subject matter of this application;

Fig. 2 is an enlarged cross-sectional plan view of one of a pair of brackets used in connection with a window;

Fig. 3 is a side elevational view of the bracket;

Fig. 4 is an end elevational view of the bracket;

Fig. 5 is an elevational view on a reduced scale of a metallic blank out of which one part of the bracket is made;

Fig. 6 is an elevational view on a reduced scale of a metallic blank out of which the second part of the bracket is made;

Fig. 7 is an elevational view on a reduced scale of a metallic blank out of which the third part of the bracket is made; and

Fig. 8 is a fragmentary side elevational view of a modified form of a curtain rod support constituting a part of the present bracket.

Referring to the present drawing in detail and 55

particularly to Fig. 1 thereof, there is shown therein in cross-section the vertical portions of window frame 10 having wall panels 11, to each of which a bracket, generally indicated by 12 is attachable. There is also shown a pair of uprightly sliding window sash frames 13 in position within said frame 10. Shade roller 14, curtain rod 15 and drapery rod 16, supported by a pair of brackets 12 are shown in Fig. 1 when in an operative position within the window.

Each of the two brackets 12 is composed of three main parts, namely, curtain rod and drapery rod supporting member, generally indicated by 17 in Fig. 2, a mounting member 18, 15 and a shade roller supporting member generally indicated by 19, each of said members is formed from suitable blank, each shown in Figs. 5, 6 and 7, respectively, and marked 17', 18', and 19', respectively. Blank 17', of an oblong shape, is 20 provided at one of its ends with a pair of spaced teeth 20, bent laterally to one side of said blank 17' and substantially on a plane perpendicular to the plane of said blank 17', for the purpose hereinafter stated. Adjacent that end said blank 25 17' is further provided with an aperture 21, and adjacent its opposite end said blank 17' has curtain rod receiving slot 22 made at its upper margin.

Said blank 17' is suitably bent and formed to 30 define a construction shown in Fig. 2, to include leg portion 23 from which said teeth 20 immediately project. The central body portion 24' and defined by lines 25 in Fig. 5, is bent to define loop 24. The further continuation of the body 35 of said blank 17', as at 26 is doubled upon said leg portion 23, and riveted thereto by rivet 27. A connecting link 28 is formed by bending the body portion of said blank 17' along line 29 so that said link 28 remains in a perpendicular relation with portion 26 and leg portion 23. The 40 opposite end portion of said blank 17' is bent along line 30 until the same remains at a right angle with relation to link portion 28 and in a parallel relative position with leg portion 23 and body portion 26, to define in a completed device, curtain rod supporting arm 31 with slot 22 therein as hereinabove indicated. Loop 24 is 45 adapted to receive a drapery rod 16 and slot 22 is adapted to receive a curtain rod 15, as seen in Fig. 1. So that the two may be spaced in a parallel relation as seen in Fig. 1, loop 24 remains away from the outer termination of the curtain rod supporting arm 31 as is seen in Fig. 2.

The mounting member 18 formed out of an oblong blank 18' includes a relatively long body

portion 32, extending to line 33, at which point said blank 18' is bent perpendicularly to said body portion 32, and in like fashion further bent along line 34 to define an end wall 35 when said mounting member 18 is fully completed, as seen in Fig. 2. This forming of said blank 18' will further define wall 36 which in the completed form of said mounting member 18, will remain in parallel relation with the body portion 32 of said mounting member 18. Further bending of said blank 18' along line 37, will define another end wall 38, which remains in a spaced, parallel relation with first end wall 35. Said end wall 38 at its free end is provided with a recess 39, and is further notched as at 40 to define a pair of spaced and comparatively narrow and short lugs 41 for the purpose hereinafter stated. Link 28 is riveted as at 42, or otherwise rigidly affixed to the outer face of wall 36, whereby said curtain rod and drapery rod supporting member 17 is in rigid relation with said mounting member 18.

The shade roller supporting member 19 is made by suitably forming blank 19' which has a generally oblong formation including central body portion 43, which in the completed form of the shade roller supporting member 19 will constitute a sliding plate 43' provided adjacent one of its ends with an oblong central slot 44. The opposite end of said body portion 43 is reduced at its two marginal edges to define an integrally formed tongue 45. Said tongue 45 adjacent its free end, and along line 46 is perpendicularly bent to define extension 47, which, in the co-operative relation in the bracket remains within the space defined by body portion or plate 32 and wall 36 of the mounting member 18, and in a perpendicular relation therewithin, and within which space it is adapted for longitudinal sliding movement with respect to said plate 32 and wall 36. Said extension 47 is provided with a threaded aperture 48 for the purpose hereinafter stated.

The opposite end of said blank 19' and along line 49 is bent perpendicularly to the body portion 43, or in the finished curtain roller supporting member 19, to sliding plate 43', and in the direction opposite from that of extension 43, to define arm 50, which in the completed bracket remains in a parallel relation with leg portion 23 of curtain rod and drapery rod supporting member 17. Arm 50, at its end marginal edge, is provided with a pair of spaced teeth 51 which are likewise bent perpendicularly to the plane of said arm 50 and into the direction of teeth 20. Teeth 20 and 51 are on the same plane.

Body portion 32 of blank 18'; or plate 32 in the finished condition of said blank 18', is provided with a pair of spaced openings 52 each adjacent the marginal edge of said plate 32, for the purpose of receiving therewithin lugs 41 wherein they are firmly set, and thereupon their ends riveted as at 53, for the purpose of maintaining end walls 35 and 38 and wall 36 in a rigidly formed position shown in Fig. 2. End wall 38 is provided with aperture 54 for the purpose hereinafter stated. The free end of said plate 32 has rigidly attached thereto a rivet 55 having a spaced head 56. The shank of said rivet 55 enters slot 44, and head 56 contacting with the adjacent face of sliding plate 43' adjacent the margin thereof defined by said slot 44, holds said sliding plate 43' in contactual relation with plate 32, and permits said plate 43' to slide in either direction, the ends of slot 44 bearing against

shank of rivet 55 limit the longitudinal movement of said plate 43' in either direction.

Rigidly attachable to arm 50 is plate 57 having a downwardly depending extension 57' provided with aperture 58 in one bracket 12 and with an oblong opening in the opposite bracket 12 for receiving the ends of the axle of shade roller and holding the same against rotation. The body portion of said plate 57, including extension 57' is bent along line 58' to deflect said body portion of said plate 57 from the remaining portion of said plate so that in the operative position of bracket 12 upon window frame panel 11, said plate 57 may remain in a spaced relation with the adjacent face of said window frame 10. Thereby said plate 57 may yield at manual pressure exerted thereupon in the direction of the window frame for insertion of the shade roller axle within opening 58. This extension 57' permits mounting of the shade roller 14 in a spaced relation with the upright horizontal bar of window frame 10 when two brackets 12 are placed upon the window frame in the nearest proximity of said horizontal vertical bar of window frame 10.

The curtain rod supporting arm 31 may be of the same width as the remaining body portion of blank 17', as is suggested in Fig. 5, or the same may be reduced in width by having the marginal portions of the adjacent end of said blank 17' cut away along lines 59 as is suggested in Figs. 3 and 4. This of course is optional.

Positioned within end walls 35 and 38, and disposed between plate 32 and wall 36, is screw 60, the outer free end whereof is reduced to form stud 61, which enters aperture 54 and wherein the same is adapted for rotary movement. The body portion of said screw 60 passes through threaded aperture 48 and consequently through extension 47. The opposite end of said screw 60 is reduced in thickness, and defines a threaded stud 62 which passes through apertures 21 and 63, the latter one made in wall 35, and which remain in an aligned relative position as is clearly seen in Fig. 2. This stud, however, is adapted for free rotary movement within said apertures 21 and 63. The outer free end of said threaded stud 62 is adapted to receive in a threaded relation therewith cap 64, terminating in a knurled knob 65. Screw 66 passes through said cap 64 and engages, in a transverse relation, said threaded stud 62 for the purpose of maintaining said cap 64 and said knob 65 in a rigid relation with said stud 62 and screw 60.

When a rotary movement is imparted to said screw 60 by manually rotating knob 65, a sliding movement to plate 43' is imparted into one or the opposite direction, depending upon the direction of turning of screw 60, by virtue of threaded engagement between said screw 60 and extension 47, said plate 43' being guided in its longitudinal sliding movement with respect to plate 32 by rivet 55 and its head 56, as hereinabove described, and recess 39 within which tongue 45 is adapted to slide.

From the hereinabove description it will be apparent that the outer end of leg portion 23 of curtain rod and drapery rod supporting member 17 and arm 50 are adapted to clamp, and by their teeth 20 and 51, to engage the edges of panel 11 of the window frame 10. The side wall of window frame 10 extending towards the window sashes 13 accommodates said plate 57 with its extension 57' for supporting said roller 14.

By imparting a rotary movement to said screw

60 in one direction, plate 43' with its arm 50 is caused to slide towards leg portion 23 whereby said leg portion 23 and said arm 50 exercise a clamping action upon window frame 10 and the respective teeth 20 and 51 bite into the adjacent portions of the window frame for the purpose of clamping and rigidly engaging the same, as is clearly seen in Fig. 1. By imparting a rotary movement to said screw 60 into the opposite direction, the clamping hold upon window frame of leg portion 23 and arm 50 will be released at which time bracket 12 may be readily removed therefrom.

The modified form of curtain rod supporting arm 31, illustrated in Fig. 8, is devoid of curtain rod receiving slot 22, but is instead provided with a pair of spaced and upwardly projecting prongs 67 to receive and engage the modified form of curtain rod which is provided at its ends with loops which may be set over one or the other of said prongs 61.

From the hereinabove description it will be seen that mounting member 18 of bracket 12 and curtain rod and drapery rod supporting member 17 of the bracket remain in a rigid relative position by virtue of rivet 42, while the shade roller supporting member 19 remains in a relative movable position with respect thereto, the same being actuated by screw 60 and guided in its movement by said screw 60, recess 39, slot 44, rivet 55 and head 56.

The drapery rod receivable within loops 24 of two brackets 12 is of the type having its ends bent perpendicularly to the body portion of the rod and said ends are simply dropped into said loops 24 from above of the two brackets, and the body portion of the drapery rod remains interposed between loops 24 of the two brackets as is clearly seen in Fig. 1.

Although Fig. 2 illustrates the left bracket, the right bracket is in all respects similar in construction thereto, except that the juxtaposition thereof is reversed as is seen in Fig. 1.

Screw 60 is brought to its ultimate operative position illustrated in Fig. 2, by first passing the same through extension 47 and within threaded aperture 48. This is done before stud 61 of said screw 60 is brought within aperture 54 in end wall 38. Thereupon the threaded stud 62 of the said screw is passed through apertures 63 and 21, and before curtain rod and drapery rod supporting member 17 and mounting member 18 are rigidly attached by rivet 42, and before wall 36 and end wall 38 are fully bent. Thereupon wall 36 is substantially brought to the position illustrated in Fig. 2 and thereupon end wall 38 is formed by bending blank 18' along line 37, inserting stud 61 within aperture 54, and thereupon lugs 41 are brought within openings 52 and hammered down to form rivets 53.

All this operation is facilitated by the fact that the blanks out of which several parts of the bracket are made, are more or less flexible and resilient permitting ready manipulation and formation thereof until the bracket is fully formed and assembled, as shown in Fig. 2.

The bracket herein shown and described, in addition for supporting shade roller, curtain rod or drapery rod, may also be used as a bathroom fixture to support towel racks, soap trays and other similar objects, without changing the construction of the bracket in any material respects.

While there is described herein a preferred embodiment of the present invention, it is nevertheless to be understood that minor changes may be made therein without departing from the spirit and scope of the invention as claimed.

What I claim as new is:

20 A bracket of the class described, comprising three members, one of said members consisting of a return-bent strip of metal providing an intermediate vertical loop adapted to receive the down-turned end of a drapery rod, one end portion of said strip being straight and terminating in a toothed window frame engaging jaw, the other end portion of said strip being directed laterally, another of said members consisting of a strip of metal having a straight end portion disposed at right angles to the straight end portion of the first-named strip, a forwardly directed portion flatly disposed against said straight end portion of the first-named strip, a portion extended backwardly parallel with the straight end portion of the second-named strip and secured to the laterally directed end portion of the first-named strip, and a second end portion directed rearwardly and secured to said straight end portion of the second-named strip, the remaining 25 30 35 40 45 50 55 60 65 70 75 80 85 90 95 100
